UNITED STATES PATENT OFFICE.

WALTER M. DANN, OF WILKINSBURG, PENNSYLVANIA, ASSIGNEE TO WESTINGHOUSE ELECTRIC & MANUFACTURING COMPANY, A CORPORATION OF PENNSYLVANIA.

TRANSFORMER RADIATOR.

Application filed April 29, 1922, Serial No. 557,325. Renewed January 24, 1927.

My invention relates to radiators, and it has particular relation to radiator elements for transformers of the oil-insulated self-cooled type.

5 One of the objects of my invention is to provide a transformer radiator in which the various units thereof are constructed of pressed metal and welded together to form a unitary structure which may be quickly 10 and easily attached to a transformer tank.

Another object of my invention is to provide a radiator, of the character described, in which the various parts are provided with flanged portions which are so disposed as to 15 be easily accessible for welding.

A further object of my invention is to provide a radiator, of the character designated, which embodies a connection adapted to secure a radiator to a tank and which 20 establishes a communication therebetween which may be constructed from a plurality of complementary pressed-metal members welded together whereby a desired number 25 of radiator units may be mounted upon a transformer tank and occupy a minimum amount of floor space.

In the accompanying drawings, Fig. 1 is a view in side elevation, of a radiator constructed in accordance with my invention.

30 Fig. 2 is an enlarged plan view of the structure illustrated in Fig. 1.

Fig. 3 is a front elevational view of the upper portion of the radiator illustrated in Fig. 2.

35 Fig. 4 is a side elevational view of the structure illustrated in Fig. 3.

Fig. 5 is an enlarged side elevational view of the member which supports the radiator upon a transformer tank and which establishes communication therebetween.

40 Fig. 6 is a horizontal sectional view on line VI—VI of Fig. 5, of one of the side portions of the connecting member.

Fig. 7 is a transverse sectional view taken 45 on line VII—VII of Fig. 5.

Referring to the drawings, a radiator constructed in accordance with my invention is shown as comprising a plurality of relatively flat envelopes or units, indicated as a whole 50 by the numeral 1, which are disposed in spaced and parallel relation with respect to

each other and connected together at their upper and lower extremities for fluid communication therebetween by means of header portions 2. The units 1 are preferably arranged in two groups with upper and lower header portions 2 of the innermost unit of each group connected to common communicating and supporting members 3 on each side thereof, which are in turn mounted 55 upon the side wall of a transformer tank 4, and which establish communication between the interior of the tank and the radiator.

Each of the units 1 consists of two complementary side members 5 and 6, respectively, of substantially dish shape, provided with outwardly extending peripheral flanges 7 adapted to be welded together to form a seamless oil-tight structure. The two side members 5 and 6 are further provided with 60 a plurality of vertically-extending stiffening ribs or corrugations 8 which extend substantially the entire length of the members and which are welded together at intervals, as indicated at 9.

75 The header portions 2 of the units 1 are formed by continuations of the side members 5 and 6 which are bent to form extruded portions 10 and 11, respectively, and which cooperate with each other, when the two side members are welded together, to form a substantially cylindrical chamber communicating with the interior of the unit. The portion 10 of each of the headers 2 is provided with an outwardly extending flange 12, and 80 the portion 11 thereof is formed with an inwardly curled edge or flange 13. When the various units of the radiator are arranged in position and welded together, the flanges 12 of the portions 10 of each header 85 extend into the portions 11 of the adjacent header member and into engagement with the inwardly extending flange 13 thereof. The flanges 12 and 13 are then welded together along their edges, as indicated at 14. 95

The headers 2 of the outermost units of the radiator are closed by cap members 15 which are provided with inwardly extending annular flanges 16 which are adapted to be welded to the flanges 13 of the headers 2.

The connecting members 3 comprise two

complementary portions 17, each of which is provided with an outwardly extending flange 18, which are adapted to be welded together along their outer edges, as indicated at 19, to form a unitary structure. Each of the portions 17 is provided with an aperture 20 the edge of which is bent inwardly, as at 21. When the parts are assembled, the outwardly extending flanges 12 of the header portions 2 of the innermost units 1 project into the apertures 20 and are welded to the flanges 21 of the member 3.

From an inspection of Figs. 6 and 7 of the drawings, it will be observed that the forward or outer portion of each of the members 3 is relatively flat and the sides thereof are so inclined that the cross-sectional area of their rear or inner portion is substantially circular and projects into a suitable connection 22 which is adapted to be detachably secured to the main tank by means of bolts 23.

In assembling the radiator constructed as above described, the various portions are built up commencing with the outermost units of each of the groups disposed on opposite sides of the member 3. That is to say, the cap portions 15 are welded in position to close the apertures in the side portions 5 of the outermost units and the side portions 6 are then welded in position on the member 5 by means of the peripheral flanges 7. The side portions 5 of the adjacent unit are then welded in position on the side portion 6 by means of the telescoping flanges 12 and 13, and a side portion 6, in turn, is welded on the side member 5. The operation is then repeated until a desired number of units have been welded together. The portions 17 of the members 3 are then separately welded to the innermost of the units 1 of each of the groups by means of the telescoping flanges 12 and 21. The two groups are then secured together by welding the portions 17 of the member 3 together along the outer edges of the flanges 18, as indicated at 19.

The inner portion of the member 3 may be tapered slightly, as indicated at 25, and is adapted to be forced into a correspondingly tapered aperture 26 in the connecting member 22 and welded thereto, as at 27.

From the foregoing it will be apparent that, by means of the above-described construction, a very strong, compact and relatively light radiator is provided that is practically an integral structure and is of neat appearance by reason of the fact that a large proportion of the welded seams are disposed within the radiator.

I claim as my invention:

1. A radiator comprising a plurality of groups of communicating radiating units, and a member disposed between said groups

and communicating therewith for establishing communication with a tank.

2. A radiator comprising a plurality of groups of communicating radiating units and a two-part member disposed between said groups and in communication therewith for establishing communication with a tank.

3. A radiator comprising a plurality of communicating radiating units and a member adapted to support said units on a tank structure and to establish communication therebetween, said member comprising a plurality of complementary portions secured together.

4. A radiator comprising a radiating element and a member for securing the same to a tank structure to establish communication therebetween, said member comprising a plurality of portions of similar shape secured together.

5. A radiator comprising a radiating element and a member for securing the same to a tank structure to establish communication therebetween, said member comprising a plurality of complementary portions of similar shape having outwardly extending flange portions adapted to be secured together.

6. A radiator comprising a radiating unit and a member for securing the same to a tank structure, said member consisting of a plurality of cooperating portions adapted to be welded together.

7. A radiator comprising a plurality of groups of radiating elements, and a member disposed between said groups for securing the same to a tank structure, said member comprising a plurality of portions of substantially similar shape and each being provided with an opening and an outwardly extending flange, said portions being adapted to be disposed in side-by-side relation with the flanges in engagement with each other and welded together with the openings in axial alignment and in communication with said groups of radiating elements.

8. A radiator comprising a plurality of groups of communicating radiating elements and a member disposed between said groups for securing the same to a tank structure, said member comprising a plurality of complementary portions of similar shape, each of said portions having a relatively flat portion provided with an opening said flat portion gradually merging into a substantially semi-cylindrical portion said members adapted to be secured together with said openings in axial alignment for communication with said elements and with said semi-cylindrical portions cooperating to form a tubular portion adapted to be secured to the tank.

9. A radiator comprising a radiating element provided with an opening surrounded by an outwardly-extending flange and a member for connecting said element to a

tank structure to establish communication therebetween, said member comprising a plurality of complementary portions, one of said portions having an opening therein surrounded by an inwardly-extending flange and into which the flange of the radiating element is adapted to project and be secured to the flanged portion thereof, said comple-

mentary portions being further provided with outwardly-extending flanges adapted to 10 be secured together after the radiating element is secured in position.

In testimony whereof, I have hereunto subscribed my name this 14th day of April, 1922.

WALTER M. DANN.
